BY

UNITED STATES PATENT OFFICE.

HENRY FREDRICK EBERT, OF NEW YORK, N. Y.

SHAVING UTENSIL.

Application filed January 31, 1922. Serial No. 532,957.

To all whom it may concern:

Be it known that I, HENRY FREDRICK EBERT, a citizen of the United States, and resident of the borough of Queens, county of 5 Queens, city and State of New York, have invented certain new and useful Improvements in Shaving Utensils, of which the following is the specification.

The object of this invention is to provide 10 a compact, self-contained shaving utensil wherein will be arranged a brush and a razor, and the relation of the parts, the means for securing them in the designated relation and the design of the container are such as to 15 make the device particularly adaptable for travellers and for those who desire their shaving implements closely associated.

Another object of the invention is to provide 20 an enclosing means for the brush, which will retain the brush in a desired shape and prevent the spreading thereof.

Another important object is to utilize the 25 handle of the brush, that is, to provide a liberal and desirable handle and to utilize the interior thereof for a useful purpose, so that the handle does not occupy lost space.

With these and other objects in view the following is what I consider the best means of carrying out my invention and the accompanying drawing should be referred to for 30 a complete understanding of the specification which follows.

In the drawing:

Fig. 1 is a side elevation, partly in section 35 and shows the complete device assembled.

Fig. 2 shows the brush portion in operative position.

Fig. 3 shows the razor containing member.

Fig. 4 shows in elevation the brush receiving means.

Fig. 5 is a plan view of the member shown in Fig. 3, but with the razor in stored position.

Fig. 6 is an end elevation of a modified 45 form.

Similar reference numerals indicate like parts in all the figures where they appear:

At 10, I show what might be considered the body member of my device as it is the 50 member with which all other parts are at some time associated.

As shown in the drawings, this member 10 consists of a cylinder having formed integral therewith a projection 11 of reduced 55 diameter. Within this reduced portion I arrange a screw-threaded cup 12 which will

be later referred to, but which is secured in the projection 11 closing one end of the cylinder against the accidental passage of water.

At the large open end of the cylinder 10, I provide a plurality of projections 13 and engaged thereon and secured over the opening of the cylinder 10 is a cap 14 having a screw-threaded perforation 15.

Secured to the inner face of the cap 14 is an open top member 16 adapted to fit closely within the member 10 and within this open top member 16, I place the handle 17 and blade supporting member 18 of a standard razor and it will be noted by referring to Fig. 5 that the container or member 16 is so proportioned as to receive the razor in close engagement, the screw-threaded projection of the razor handle 17 enters the screw-threaded perforation 15 in the cap 14 and when screwed therein will not only retain itself, but also the blade supporting member against vibration and rattle. Obviously, the cap 14 is provided with an overhanging flange 20 and recesses 21 for engagement with the projections 13.

Screw-threaded into the cup member 12 is the brush 22, the bristles of which are secured in a head 23 which should be formed of metal and surrounding the brush 22, when not in use, is a casing 24 which casing is provided with perforations 25.

One end of the casing 24 is of a reduced diameter as shown at 26, this reduced portion is intended to fit closely upon the reduced portion 11 of the member 10 and the flange 27 upon the brush head 23 will engage the shoulder 28 of the casing 24 and will retain this casing in place associated with the member 10 as shown in Fig. 1, when the screw-threads 23 of the brush head engage the screw-threads of the cup member 12.

At the outer end of the member 24 I may arrange a cap 29 similar to the cap 14, previously described, with the exception that no screw-threaded perforation 15 is required in the cap 29.

When the brush is in use as shown in Fig. 2, the enclosing member 24 is laid aside and when the razor is in use, the member 16 may also be laid aside or may be replaced within the member 10 after the razor has been removed.

I call particular attention to the opposed finger openings 30 and 31 in the member 24,

and which are provided to allow the user to engage with the fingers the flange 27, when the brush is in the container 24, so that the head of the brush may be screwed 5 into the cup 12 to retain the parts as shown in Fig. 1.

The size and dimensions of all parts may be changed at will, the member 10 may be of any shape desired, the number of 10 ventilating perforations 25, in the member 24 which allow evaporation from the brush and assist in the drying thereof may be increased or decreased and the diameter of these perforations may be changed at will.

15 Other modifications may be made within the scope of the appended claims.

Having carefully and fully described my invention what I claim is:—

1. A shaving utensil having a plurality of 20 cylindrical casings in longitudinal alignment and each provided with reduced portions, a screw-threaded cup member secured under the reduced portion of one said cylindrical member, a brush having a screw-threaded head adapted to engage in said cup and means upon said brush head for retaining the other said cylindrical member around said brush.

2. A shaving utensil comprising a plurality of casings in alignment, each having a portion of reduced cross-sectional area, a 30 screw-threaded cup within one said reduced portion and secured therein, a brush having a screw-threaded head and a flange 35 and adapted to be engaged through the other said casing and into said cup, said flange securing the reduced portion of said second casing, over the reduced portion of the first said casing.

40 3. A shaving brush comprising a plurality of casings in alignment, one of which is adapted to be received within another and two of which are provided with reduced

portions, one reduced portion being adapted to be secured over another reduced portion, a screw-threaded cup within one reduced portion and a brush head having a flange adapted to engage the other said reduced portion and a screw-thread adapted to be received in said cup, to retain the whole 50 secured.

4. In a device of the character described, a plurality of casings, each having a reduced portion, caps for the free ends of said casings, a screw-threaded member in the reduced portion of one said casing and means co-operating with said screw-threaded member for securing said casings together, said means comprising a brush having a screw-threaded head and a flange adapted to engage the shoulder formed by the reduced portion of one said casing.

5. In a device of the character described, a plurality of casings, each having a reduced portion, caps for the free ends of said casings, a screw-threaded member in the reduced portion of one said casing and means co-operating with said screw-threaded member for securing said casings together, said means comprising a brush having a screw-threaded head.

6. In a device of the character described, a plurality of casings, each having a reduced portion, caps for the free ends of said casings, a screw-threaded member in the reduced portion of one said casing and means co-operating with said screw-threaded member for securing said casings together, said means comprising a brush having a screw-threaded head, one of said casings being provided with finger recesses to allow the rotation of said brush head.

Signed at the borough of Brooklyn, county of Kings, city and State of New York, this 23d of January, 1922.

HENRY FREDRICK EBERT.
